UNITED STATES PATENT OFFICE.

STEPHEN E. ISGETT, OF GILBERT, LOUISIANA.

FURNACE-DOOR FOR BRICK-KILNS.

1,269,450.

Specification of Letters Patent. Patented June 11, 1918.

Application filed October 11, 1917. Serial No. 196,063.

To all whom it may concern:

Be it known that I, STEPHEN E. ISGETT, a citizen of the United States, residing at Gilbert, in the county of Franklin and State 5 of Louisiana, have invented a new and useful Furnace-Door for Brick-Kilns, of which the following is a specification.

The subject of this invention is a furnace door intended for use, principally with 10 brick kilns, and like structures.

The main object of the invention is the production of a door which will effect a saving in the consumption of fuel.

Another object of the invention is to provide 15 a sight slide for the door.

A further object is to provide means for feeding gas or oil to the furnace.

Still another object is to provide a simple, durable and efficient furnace door.

20 With the foregoing and other objects in view which will appear as the description proceeds the invention resides in the combination and arrangement of parts and in the details of construction hereinafter described and claimed, it being understood that changes in the precise embodiment of the invention herein disclosed, can be made within the scope of what is claimed without departing from the spirit of the invention.

25 A practical embodiment of the invention is shown in the accompanying drawing, wherein:—

Figure 1 is a front elevation of the door shown applied to a kiln;

30 Fig. 2 is a rear elevation of the door;

Fig. 3 is a section on the line 3—3 of Fig. 2;

Fig. 4 is a perspective view of the supporting or hanging lug;

35 Referring to the drawing by numerals of reference:—

A portion of the kiln is indicated at 1 and anchored in the wall of the kiln are the brackets or hangers consisting of an arm 40 2 provided with an angled end to contact the inner face of the kiln, and with a cross bar 3 the down turned ends of which are adapted to take over the ends of a brick in the kiln wall.

45 The door consists of a casing 4 formed with rearwardly extending side flanges 5 and upper and lower flanges 6. The upper and lower flanges are extended beyond the sides to provide lugs.

50 The lugs 7 extending beyond the front

edge of the door at the upper and lower corners are apertured to receive a bolt 8 which is spaced from the front edge of the door and serves to strengthen the structure. A hook 9 is bound by the bolt 8 upon 60 the upper lug 7, or it may be integral with the lug, to form a grapple for opening the door.

The lugs 10 at the upper and lower corners of the rear edge of the door are also 65 apertured to receive a bolt 11, which binds the parts in place and spaced from such apertures are other apertures which align with the apertures in the arms 2 and receive a pin 12 by which the door is hinged to the 70 brackets.

Guides 13 are secured to the front of the casing 4, toward the upper edges thereof, and within these guides a slide 14 is mounted for reciprocation. The slide 14 is provided 75 with an out turned end 14' by which the slide may be reciprocated back and forth, and also with spaced apertures 15 which are adapted to align with apertures 16, formed in the casing, when the slide is in one position.

Guides 17 extend from the front face of the casing toward the lower edge thereof, and a slide 18 reciprocates within these guides. The slide 18 has an angled end 18' 85 by which the slide may be reciprocated and is provided with apertures 19 which are adapted to align with apertures 20 formed in the casing 4. 90

A slot 21 is provided in the slide 18 and extends longitudinally thereof through a portion of the length of the slide.

This slot permits exposure of an aperture 22, formed in the casing 4, at all positions of the slide 18. 95

The aperture 22 is provided to permit insertion of a gas or oil burning nozzle.

The back of the door is formed of fire 100 bricks 23 which are embraced by the rearwardly extending flanges 5 and 6. The bricks are provided with apertures 24 which align with the apertures 16, 20 and 22 of the casing.

A sheet of asbestos 25, or other heat insulating material, may be interposed between the bricks 23 and the casing so as to protect the casing from undue heating. 105

As will be seen, the sight slide 14 may be reciprocated to allow inspection of the in- 110

terior without opening the door. This not only protects the attendant from the intense heat and glare of the fire, but also protects the arch from injury due to the sudden change in temperature and saves fuel.

The slide 18 provides draft for the furnace and the slide 14 may also be used as an adjunct thereto for draft purposes, when desired.

The aperture 22 may be plugged in any suitable manner when gas or oil is not being used.

It has been found that the friction between the brackets and the lugs 10 is sufficient to hold this door in its closed position; consequently a latch for the door has not been provided or shown.

Having thus described the invention,

what is claimed as new and sought by Letters Patent, is:

The combination with an apertured kiln wall, including brackets anchored therein, of a door swung from the brackets, said door comprising a casing provided with sight apertures and draft openings, means secured to the casing for closing the sight openings, means secured to the casing for regulating the draft openings, and fire brick secured to the back of the casing.

In testimony that I claim the foregoing as my own, I have hereto affixed my signature in the presence of two witnesses.

STEPHEN E. ISGETT.
